CLAIM

We claim the ornamental design for a defibrillator, substantially as shown and described.

DESCRIPTION

FIG. 1 is a first perspective view of a defibrillator showing our new design.

FIG. 2 is a second perspective view thereof.

FIG. 3 is a top view thereof.

FIG. 4 is a bottom view thereof.

FIG. 5 is a back view thereof.

FIG. 6 is a front view thereof.

FIG. 7 is a left side view thereof; and,

FIG. 8 is a right side view thereof.

The broken lines in the drawings depict portions of the defibrillator that form no part of the claimed design.

1 Claim, 8 Drawing Sheets
